Fig. 10.

Fig. 11.

Fig. 12.

Fig. 13.

FIG. 1 is a rear perspective view of a baseball mitt showing a preferred embodiment of my new design;

FIG. 2 is a rear perspective view of the baseball mitt of FIG. 1, taken from a different position than FIG. 1;

FIG. 3 is a rear-end perspective view of the same;

FIGS. 4 and 5 are respectively, rear-end and back perspective views of a baseball mitt showing a modified form of my new design;

FIGS. 6, 8 and 10 are each, back perspective views of baseball mitts showing additional modifications of my new design;

FIGS. 7, 9 and 11 are each, rear-end perspective views of the baseball mitts shown respectively, in FIGS. 6, 8 and 10;

FIGS. 12 and 13 are respectively, side and front perspective views of the baseball mitts depicted in any of FIGS. 1, 5, 6, 8 and 10.

This is a continuation of my copending applications, D-23,724, D-23,725, D-23,726, D-23,727, and D-23,736, all filed on June 29, 1970 and now abandoned.

I claim:

The ornamental design of a baseball mitt, substantially as shown and described.
